WILLIAM M. HORTON, OF CLEVELAND, OHIO, ASSIGNOR TO THE ADAMS-BAGNALL ELECTRIC COMPANY, OF CLEVELAND, OHIO, A CORPORATION OF OHIO.

AUTOMOBILE-HEADLIGHT.

1,321,444.

Specification of Letters Patent. Patented Nov. 11, 1919.

Application filed December 6, 1916. Serial No. 135,321.

To all whom it may concern:

Be it known that I, WILLIAM M. HORTON, a citizen of the United States, residing at Cleveland, in the county of Cuyahoga and 5 State of Ohio, have invented certain new and useful Improvements in Automobile-Headlights, of which the following is a specification.

This invention relates to headlights, a 10 pair of automobile headlights being shown herein, it more particularly relating to improved means for shifting the reflectors of such headlights simultaneously in various directions, whereby when the reflectors are 15 shifted in one direction, the glare of such headlights will be prevented, while by shifting them in other directions increased efficiency thereof will be obtained, one of the 20 objects of the invention being to provide electrically operative means for shifting such reflectors in different directions.

In the drawings accompanying and forming part of this specification, Figure 1 is a horizontal sectional view of a pair of conventional headlights, such as those usually used for automobiles with the reflectors thereof connected for simultaneous movement in different directions; Fig. 2 is a front view of the structure shown in Fig. 3; and Fig. 3 is an enlarged sectional view of the electric operating means or motor for shifting the reflectors, this view being taken on line 3—3 of Fig. 2, and looking in the direction of the arrows in said figure. Similar characters of reference indicate corresponding parts in the several figures of the drawings.

In the present improvement, each headlight comprises a casing 2 of any suitable 40 design or shape, having a lens 3 attachable thereto in any desired manner. Each casing is provided with a reflector of some suitable form,—in the present instance the reflector of the right hand lamp in Fig. 1 is 45 designated as 4, and the left hand reflector as 4'; each reflector carries the usual bulb or light 5 connected with the source of electrical energy in the usual manner, whereby the light is movable with the reflector. Each 50 reflector is provided with a pair of oppositely located pivot pins 6, each loosely supported by a pivot ball 7, each of which ball is movably carried in a slotted member or tube 8, secured to the inside wall of the cas-

ing. This pivot construction permits the 55 reflector to swing up or down on its pivot pins relatively to the balls, which support such pins and also permits the reflector to be swung in a direction transverse to its up and down movement due to the movement of the pivot pins and balls within the slotted tubes, and also permits the reflectors to be swung by a combination of these two movements in such a way that the light may be thrown into different angular positions, 60 so that when the reflector is thrown down the glare of the lamp will be entirely prevented, while when thrown sidewise, a better view of the road is obtained, especially when going around corners or curves, while 65 when these two movements are combined sign posts can be read, thus insuring greater efficiency in the use of the headlights. For swinging the reflectors up and down, or to return them to their horizontal position, 70 one of the reflectors, as 4, is connected by a rod 9 through the medium of a universal connection 10, as by a ball and socket with an eccentric 11, mounted on a shaft 12, on which is secured a ratchet wheel 13 adapted 75 to be engaged by a pawl 14 pivotally carried by a pair of arms 15 secured to the shaft 12. The opposite end of this pawl projects as at 16 into a slot 17 of a core or plunger 18, whereby on the movement of the core back 80 and forth the pawl will be operated to rotate the ratchet wheel, it being maintained in operative engagement with such ratchet wheel by a spring 19 secured to a bracket 85 20 fastened to the rear of the casing 2. This 90 bracket supports the several parts of the motor mechanism 30. The spring 19 is in position to always return the core or plunger 18 to its forward position when it has been drawn rearward or backward by the 95 magnet 21, which is carried by the bracket adjacent to the core or plunger. The ratchet wheel is maintained against slipping backward by a suitable spring pawl 19', also carried by the bracket 20. The core 18 has a 100 contact member 22 at its forward end in position to make contact with a similar contact member 23 carried by a spring member 24 supported on a rigidly upstanding member 25 insulated from the bracket 20. The 105 spring 19 is in position to always return the core or plunger 17 to its forward position to make contact with the armature or

spring contact member 24 after such core 18 has been drawn to the rear or backward by the magnet. In other words, the spring 19 acts through the pawl 14 to return the 5 core or plunger into position to make contact after such contact is broken by the electro-magnet means, so that when the mechanism is put in operation there is a continuous make and break between the contact 10 portions of the core 17 and the member 24, to thus rotate the ratchet wheel 13 and thereby through the eccentric 11 shift the reflector, with which it is connected, upwardly or downwardly to the desired extent, the 15 reflector at this time swinging on its pivot pins relatively to the balls. It will of course be understood that the necessary insulations and electrical connections not necessary to describe herein are provided to insure the 20 proper operation of the electro-magnet or motor. A further detail description of this motor and the electrical connections is deemed unnecessary herein as the same is described in my contemporaneously pending 25 application filed December 2, 1916, Serial No. 134,625.

The two reflectors are connected by a connecting rod 26 shown as comprising a pair of rods coupled together by a coupling 30 27, each member of the pair being pivotally connected with an ear or lug 28 secured to the reflector. The rod 26 extends through enlarged or slotted openings 29 of the lamp casings, so that when the reflector 4 is shifted 35 up or down the companion reflector 4' will move therewith. A similar motor 30' is placed in the present instance in the lamp casing carrying the reflector 4', but set at right angles to the setting of the motor 30 just described, and an eccentric 31 which 40 is similar to the eccentric 11 hereinbefore referred to, is therefore located at right angles to the eccentric 11, it being likewise suitably connected by links 32 with the 45 connecting rod 26 connecting the two reflectors, or a sleeve 20' thereof, whereby on the operation of the motor 30' in a similar manner to the motor 30 hereinbefore described, the reflector 4' will be shifted at 50 right angles to its up and down movement due to the shifting of the balls in the tubular members or raceways, one in one direction and the other in the opposite direction, that is, one forwardly and the other rearwardly, and consequently through the connecting rod 26 the companion reflector 4 will 55 also be shifted in a similar manner. To insure the proper parallel movement of the reflectors, they are also connected by a connecting rod 33, comprising a pair of members coupled together by a coupling member 34, one of the rod members as 35 being linked by a pair of links 36 to one of the reflectors shown herein as the reflector 4. 60 This rod 33 extends through enlarged open-

ings or slots 37 in the two casings. The linkage connection 36 provides the proper flexible connection between the two reflectors to permit proper movement thereof when shifted, while the universal connection 70 or some similar flexible connection 10 provides the necessary connection to permit movement of the reflectors by the motor 30' in a manner which will be readily understood. Each motor will be controlled by a proper switch and when the switch of the motor 30 is operated, both reflectors will be swung up or down from their horizontal position in the manner desired, and when the switch of the motor 30' is operated, both 80 reflectors will be swung sidewise or transversely of their up and down movement. Obviously a combination of these up and down or sidewise movements can be readily obtained by shifting the reflectors sidewise, 85 and then while in such angular position shifting them up or down or vice versa, so that the reflectors in the present improvement may be shifted in such manner that movements between these two planes of 90 movement may be obtained when desired.

It will be understood that the various details may be more or less changed without departing from the spirit or scope of the present improvement. 95

Like my companion case hereinbefore referred to, the pawls may be operated mechanically instead of electrically if preferred.

It will of course be understood that the 100 slotted tubes maintain the balls in proper position, the slots of the tubes being of suitable width to receive the pins 6 and prevent the improper displacement of the balls.

It will be observed that in the present improvement the reflector is itself directly connected with the casing, thus doing away with all intermediate connections, such as annular members, etc., by compound pivotal means, thus materially simplifying the mechanism 105 and reducing the expense of manufacturing the same. It will also be understood of course that the switches for controlling the motors can be located in any desired place, as on the steering wheel or dash board of the 110 vehicle. In practice, of course, the connecting rods between the two reflectors may be located closer together and in fact may run through a suitable tube, if desired. 115

I claim as my invention:

1. The combination of a lamp casing, a shiftable reflector therein, means for supporting the reflector on a shiftable horizontal axis for tilting movement up or down, said axis being shiftable in a horizontal plane 120 whereby a combination of these movements will effect the movement of the reflector in different angular positions, and electrically operative means for shifting the reflector. 125

2. The combination of a lamp casing, a 130

shiftable reflector therein, a pair of compound pivots for supporting the reflector at opposite sides and each compound pivot comprising a pair of directly connected pivots 5 and a guideway carrying one of said pivots, one connected with the reflector and another with the casing and effective to permit horizontal movement of the reflector and also the tilting thereof in every position of horizontal 10 movement which the reflector may assume, and means for shifting the reflector.

3. The combination of a lamp casing, a shiftable reflector therein, compound pivotal means for directly connecting the reflector 15 with the casing and comprising a pair of pivot pins and a pair of balls, means for guiding said pivotal means, and means for shifting said reflector.

4. The combination of a lamp casing, a shiftable reflector therein, compound pivotal 20 means for supporting the reflector at opposite sides thereof for tilting movement up and down and for sidewise movement in a horizontal plane, said reflector being tiltable 25 in every position of horizontal movement which the reflector may assume, and means for shifting the reflector.

5. The combination of a lamp casing, a shiftable reflector therein, compound pivotal 30 means for directly connecting the reflector with the casing and comprising a pair of pivot pins and a pair of balls, means for guiding said pivotal means, and electrical means for shifting said reflector.

35 6. The combination of a lamp casing, a shiftable reflector therein, means for pivotally supporting the reflector at opposite sides and comprising a pair of compound pivotal means each including a pivot pin and a pivot 40 ball, means for guiding said ball, the reflector and casing carrying one the pivot and ball and the other the guiding means therefore, said pivot and pivot ball being movable together and also relatively to each other, 45 and electrically operative means for shifting the reflector.

7. The combination of a lamp casing, a reflector pivotally supported therein for tilting movement up and down and for movement 50 in a horizontal plane said reflector being tiltable in every position of horizontal movement which the reflector may assume, and means for shifting the reflector and including a connector having a universal connection with the reflector.

55 8. The combination of a lamp casing, a shiftable reflector therein, means for supporting the reflector and comprising a pair of oppositely located pivot pins secured to the reflector, a pair of balls in which the pivot pins rotate, slotted members carried by the casing for receiving said balls, and means for shifting the reflector.

9. The combination of a lamp casing, a shiftable reflector therein, means for sup- 60 65

porting the reflector and comprising a pair of oppositely located pivot pins, a pair of balls in which the pivot pins rotate, one of said last two parts connected with the reflector, slotted members carried by one of said first two parts for receiving said balls, and means for shifting the reflector. 70

10. The combination of a lamp casing, a shiftable reflector therein, means for supporting the reflector on a horizontal shift- 75 able axis for tilting movement up and down, means for shifting the reflector up or down, means for shifting the reflector and its axis sidewise, the organization being such that the reflector may be shifted by a combination 80 of these movements into various angular positions, each of said shifting means including electrically operative means.

11. The combination of a lamp casing, a shiftable reflector therein, means for sup- 85 porting the reflector on a horizontal shiftable axis for tilting movement up and down, means for shifting the reflector up or down, means for shifting the reflector and its axis sidewise, the organization being such that 90 the reflector may be shifted by a combination of these movements into various angular positions, each of said shifting means including a make and break electrically operative means carried by the casing. 95

12. The combination of a lamp casing, a shiftable reflector therein, means for supporting the reflector on a horizontal shiftable axis for tilting movement up and down, means for shifting the reflector up or down, 100 means for shifting the reflector and its axis sidewise, the organization being such that the reflector may be shifted by a combination of these movements into various angular positions, each of said shifting means 105 comprising an electromagnet having a shiftable core, a pawl operated thereby, a ratchet wheel operated by said pawl, an eccentric operated by said ratchet wheel and connected with the reflector, and a spring for controlling the movement of the core and thereby 110 the pawl in one direction.

13. The combination of a pair of headlight casings, a pair of reflectors pivotally supported therein for movement in trans- 115 verse directions, a pair of eccentrics connected to each of the reflectors, means for connecting the reflectors for simultaneous movement, and means for operating the eccen- trics. 120

14. The combination of a pair of headlight casings, a pair of reflectors pivotally supported therein for movement in trans- verse directions, a pair of eccentrics connected to each of the reflectors, and means 125 for operating the eccentrics and comprising electrically operative means.

15. The combination of a pair of headlight casings, a pair of reflectors, compound pivotal means for supporting each of the 130

- reflectors, electrical means for operating the reflectors in one direction, and an independent electrical means for operating the reflectors in another direction.
5. 16. The combination of a pair of head-light casings, a pair of reflectors, compound pivotal means for supporting each of the reflectors, electrical means for operating the reflectors in one direction, and an independent electrical means for operating the reflectors in another direction, each of said electrical means comprising an electric motor.
15. 17. The combination of a pair of head-light casings, a pair of reflectors, compound pivotal means for supporting each of the reflectors, electrical means for operating the reflectors in one direction and an independent electrical means for operating the reflectors in another direction, each of said electrical means comprising an electric motor, one located in each casing and set at right angles to the other.
25. 18. The combination of a pair of lamp casings, a shiftable reflector in each of said casings, means for supporting each of said reflectors for substantially universal movement, means connecting the reflectors for simultaneous movement, and means for shifting the reflectors in different directions and including a make and break electrically operative means.
35. 19. The combination of a pair of lamp casings, a shiftable reflector in each of said casings, means for supporting each of said reflectors for substantially universal movement, means connecting the reflectors for simultaneous movement, and means for shifting the reflectors in different directions and including a make and break electrically operative means comprising a pair of motors.
45. 20. The combination of a pair of lamp casings, a shiftable reflector in each of said casings, means for supporting each of said reflectors on a shiftable horizontal axis for tilting movement up or down, said axis being shiftable in a horizontal plane, means connecting the reflectors for simultaneous movement, and means for shifting the reflectors in different directions and including a make and break electrically operative means comprising a pair of motors, one located in each casing.
55. 21. The combination of a pair of lamp casings, a shiftable reflector in each of said casings, means for supporting each of said reflectors on a shiftable horizontal axis for tilting movement up or down, said axis being shiftable in a horizontal plane, means connecting the reflectors for simultaneous movement, and means for shifting the reflectors in different directions and including a make and break electrically operative means comprising a pair of motors, one located in each casing.
65. 22. The combination of a pair of lamp casings, a shiftable reflector in each of said casings, means for supporting each of said reflectors on a shiftable horizontal axis for tilting movement up or down, said axis being shiftable in a horizontal plane, means connecting the reflectors for simultaneous movement, and means for shifting the reflectors in different directions and including a make and break electrically operative means comprising a pair of motors, one located in each casing and one operative to shift the reflectors in certain directions and the other operative to shift the reflectors in different directions.
70. 23. The combination of a pair of lamp casings, a shiftable reflector in each of said casings, means for supporting each of said reflectors on a shiftable horizontal axis for tilting movement up or down, said axis being shiftable in a horizontal plane, means connecting the reflectors for simultaneous movement, and means for shifting the reflectors in different directions and including a make and break electrically operative means and comprising a pair of motors, one located in each casing and one operative to shift the reflectors in certain directions and the other operative to shift the reflectors in different directions and located one at right angles to the other.
75. 24. The combination of a pair of lamp casings, a shiftable reflector in each of said casings, means for supporting each of said reflectors on a shiftable horizontal axis for tilting movement up or down, said axis being shiftable in a horizontal plane, means connecting the reflectors for simultaneous movement, and means for shifting the reflectors in different directions and including a make and break electrically operative means and comprising a pair of motors, one located in each casing and one operative to shift the reflectors in certain directions and the other operative to shift the reflectors in different directions and located one at right angles to the other, and said motors being a duplicate one of the other.
80. 25. The combination of a pair of lamp casings, a shiftable reflector in each of said casings, means for supporting each of said reflectors on a shiftable horizontal axis for tilting movement up or down, said axis being shiftable in a horizontal plane, means connecting the reflectors for simultaneous movement, and means for shifting the reflectors in different directions and including a make and break electrically operative means and comprising a pair of motors, one located in each casing and one operative to shift the reflectors in certain directions and the other operative to shift the reflectors in different directions and located one at right angles to the other, and said motors being a duplicate one of the other, each comprising an electro-magnet, a shiftable core, a pawl connected with the core, a ratchet wheel operated by the pawl, a spring for controlling the movement of the pawl in one direction, and means connecting the reflectors with the ratchet wheels.
85. 26. The combination of a pair of lamp casings, a reflector in each of said casings, means connecting the reflectors for simultaneous movement, compound pivotal means for pivotally supporting each reflector with-
90. 95. 100. 105. 110. 115. 120. 125. 130.

in its casing, and a pair of duplicate electrically operating means for shifting the reflectors.

26. The combination of a pair of lamp casings, a reflector in each of said casings, means connecting the reflectors for simultaneous movement, compound pivotal means for pivotally supporting each reflector within its casing, and a pair of duplicate electrically operating means for shifting the reflectors, each located in a lamp casing.

27. The combination of a pair of lamp casings, a reflector in each of said casings, means connecting the reflectors for simultaneous movement, compound pivotal means for pivotally supporting each reflector within its casing, and a pair of duplicate electrically operating means for shifting the reflectors, each located in a lamp casing and 20 one at right angles to the other.

28. The combination of a pair of lamp casings, a reflector in each of said casings, means connecting the reflectors for simultaneous movement, compound pivotal means for pivotally supporting such reflector within its casing, and a pair of duplicate electrically operating means for shifting the reflectors, one operative to shift the reflectors in certain directions and the other operative 30 to shift the reflectors in different directions.

29. The combination of a pair of lamp casings, a reflector in each of said casings, means connecting the reflectors for simultaneous movement, compound pivotal means 35 for pivotally supporting each reflector within its casing, and comprising a pair of pivots and a pair of pivotal balls supported within the casing, and duplicate means for operating the reflectors.

40. 30. The combination of a pair of lamp casings, a reflector in each of said casings, means connecting the reflectors for simultaneous movement, compound pivotal means

for pivotally supporting each reflector within its casing, and comprising a pair of pivots 45 and a pair of pivotal balls supported within the casing, and duplicate means for operating the reflectors, one for operating the reflectors in certain directions and the other in different directions.

31. The combination of a pair of lamp casings, a reflector in each of said casings, means connecting the reflectors for simultaneous movement, compound pivotal means for pivotally supporting each reflector within its casing, and comprising a pair of pivots 55 and a pair of pivotal balls supported within the casing, and duplicate means for operating the reflectors, one for operating the reflectors in certain directions and the other in 60 different directions, said duplicate means comprising a pair of electrical motors located within the casings, one at right angles to the other.

32. The combination of a pair of lamp casings, a reflector in each of said casings, means connecting the reflectors for simultaneous movement, compound pivotal means for pivotally supporting each reflector within its casing, and a pair of duplicate electrically operating means for shifting the reflectors, and each comprising a make and 70 break electric motor.

33. The combination of a pair of lamp casings, a reflector supported in each of said 75 casings for tilting movement up or down and sidewise movement, a pair of means each connecting the reflectors for simultaneous movement, and insuring a parallel movement thereof, and means for shifting the reflectors, one of said connecting means including a flexible connection.

Signed at Cleveland, county of Cuyahoga, State of Ohio, this 4th day of December, 1916.

WILLIAM M. HORTON.
